UNITED STATES PATENT OFFICE

MONROE RULE, OF SWEETWATER, TEXAS

PLASTER-BOARD-EDGE PROTECTION

Application filed March 18, 1927. Serial No. 176,335.

This invention relates to apparatus for the manufacture of plasterboard, but more particularly to the means for drying the plasterboard in the kiln after it leaves the forming machine and the plastic core has become set.

Heretofore in drying plasterboard in such kilns, trouble has been experienced with the edges of the board. The drying effect of the heat of the kiln is supplemented by a blast 10 of air through the kiln to more readily and more rapidly carry off the excess moisture. The edges of the plasterboard have a larger surface comparatively than the central portion of the board and are dried more rapidly. 15 This is particularly true in the "wet end" of the kiln. As the board advances further into the kiln the heat of the kiln applied to the already dried edges is sufficient to start a calcination of the gypsum core at the edge 20 while the central portion is not so affected. This is the result of the uneven drying of the various portions of the board.

It is an object of this invention to provide a means whereby the edges of the board may 25 be protected in the wet end of the kiln and to produce a more even drying of the board. This has the effect of preventing the calcining of the edges of the plasterboard in the kiln during the drying of the board.

30 In the drawing in which like numbers indicate like parts, Fig. 1 is a transverse cross section showing three decks of such a kiln with the baffles both fixed and adjustable, of the new device in various positions for the 35 fabrication of board of different widths. Fig. 2 is a longitudinal section of two decks of such a kiln showing the conveyor, the pipes for heating the kiln and the method of using the baffles. Fig. 3 is a detail showing the 40 mounting of an adjustable baffle. Fig. 4 is a cross section of Fig. 3 taken through the line 4-4, while Fig. 5 is a cross section through Fig. 3 along the line 5-5. Fig. 6 is a detailed drawing showing the method of installing the adjusting rod through the side of 45 the kiln.

Referring now more particularly to the drawing in detail, fixed baffles 1 are mounted on the stem pipes along the side of the kiln 50 extending downwardly therefrom at a fixed

angle and extending along and riding the edges of the plasterboard 8. In the central portion of the kiln movable baffles 2 are mounted similar to the fixed baffles along the sides but are capable of lateral movement, a rod 3 being attached thereto and extending through the side of the kiln 11. It is contemplated mounting the baffles on the steam pipe 5 which extends transversely to the kiln and holding them in place at a fixed angle to the plasterboard by means of rods 7 placed adjacent to the steam pipe 5. The mounting of the movable baffle is more clearly shown in Figs. 4 and 5. The adjustable baffle 2 is attached to the adjusting rod 3 by means of bolts and nuts 6 substantially as shown, alternate sections of the baffle embracing in opposite directions the rod 7 placed adjacent to the stem pipe 5 for the purpose of maintaining the angular relation between the baffles 70 and the plasterboard. The fixed baffles 1 are similarly mounted except that there is no adjusting rod 3 or nuts and bolts 6. In order that there will be little heat loss around the adjusting rod 3 a joint, or rather an opening, 75 through the side wall of the kiln is provided as shown in Fig. 6. In this drawing a bushing 9 which fits snugly around the adjusting rod 3 extends through the walls of the kiln 11 and is threaded on both ends. This bushing is held in place by nuts 10 on both sides of the kiln wall.

80 In the operation as the plasterboard carrying its excess moisture is introduced at the wet end of the kiln it may be placed on any one of several decks. Before its is introduced, however, the movable baffles 3 are so adjusted laterally that the movable baffle 2 will ride one edge of the board while the fixed baffle 1 will ride the outside edges of the 85 board. The board advances along the rollers or conveyor 4 and due to the angular relation of the baffle slips thereunder. Each baffle extends a sufficient length so that the next succeeding baffle in the same relative position 90 overlaps it providing a continuous protection to the edges of each sheet as it passes through the kiln. These baffles prevent the blast of air from reaching the tops of the edges and thus insure a more even drying of the board. 95 100

Having thus described my invention, what I claim is:

5. In the process of making plasterboard and combined therewith, the method of protecting the edges of the plasterboard during kiln drying, comprising the covering of the edges of such plasterboard with protecting strips as the board passes through the kiln.
10. A device to be located within a plasterboard drying kiln consisting of a plurality of baffles composed of long narrow strips of sheet metal, means for supporting one end of each of the baffles, and means for laterally adjusting certain of the baffles from the exterior of the kiln.
15. In the drying of plasterboard after forming, a device to protect the edges of the plasterboard comprising a plurality of baffles to cover the edges, certain of such baffles being laterally adjustable, long narrow strips of sheet metal one end of which is supported the other end being overlapped by the next succeeding baffle.
20. In the kiln drying of plasterboard during its manufacture a device to protect the edges of the plasterboard from burning consisting of a series of baffles at the wet end of the kiln, the baffles at the side of the kiln being fixed in place the centrally located baffles being capable of lateral adjustment and means to make such adjustment.
25. In a drying kiln for plasterboard manufacture a device to protect the edges of the plasterboard consisting of a plurality of baffles of long narrow strips of sheet metal placed to ride the edges of the plasterboard, the side baffles being fixed, the central baffles being laterally adjustable, supports to fasten one end of each baffle and means to adjust the central baffles from the exterior of the kiln.
30. In a plasterboard drying kiln means for moving plasterboard therethrough and means for drying the plasterboard in combination with means to protect the edges of the plasterboard comprising a plurality of metal baffles engaging the top of the edges of the plasterboard as it advances under the baffles.
35. In a kiln for drying plasterboard a plurality of widths of plasterboard moving simultaneously therethrough, and means for protecting the edges of the plasterboard moving through the kiln comprising a plurality of fixed and adjustable baffles sliding thereover.
40. In a kiln for drying plasterboard a plurality of decks each having a plurality of widths of plasterboard thereon; means for providing movement to the plurality of layers and widths of plasterboard; steam pipes for applying heat to the kiln placed transverse thereto; metallic rods spaced from and adjacent to certain of such steam pipes; a plurality of flexible baffles on each deck extending downwardly from said certain steam

70. pipes at an angle to the plasterboard, and sliding over the moving plasterboard, supported by the steam pipes and anchored thereto, the angle being maintained by attaching the baffle to the steam pipes and the adjacent metallic rods; a plurality of laterally adjustable baffles mounted on the steam pipes and rods similarly to the fixed baffles; and means to make the lateral adjustment extending from the interior to the exterior of the kiln.

75. 9. In the process of making plasterboard which comprises advancing the plasterboard through the drying kiln while maintaining the plasterboard in contact with superimposed baffles which inhibit the direct impact of the hot kiln gases with the plaster bound edges of said plasterboard.

80. 10. A drying kiln for plasterboard comprising a conveyor adapted to accommodate a plurality of widths of plasterboard, steam pipes for applying heat to the kiln, a plurality of flexible sheet metal baffles attached to said steam pipes, said baffles in the center portion of the kiln being laterally adjustable on the pipe coils, and means to move said adjustable baffles.
